Application filed September 30, 1895. Serial No. 564,217. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of a series of basket-shaped figures filled with flowers and leaves and placed at certain distances apart, with sprays of flowers and leaves hanging from said basket-shaped figures and a lyre-shaped ornament placed between the basket-shaped figures and inclosed by the sprays of flowers and leaves hanging from the basket-shaped figures, with small festoons of flowers and leaves hanging from said lyre-shaped ornaments, as represented in the accompanying

drawing. The border of said design is also formed of basket-shaped figures filled with flowers and leaves, with sprays of flowers and leaves springing from the base of said figures and lyre-shaped ornaments arranged on each side of said basket-shaped figures, with small festoons of flowers and leaves hanging from said lyre-shaped ornaments, as shown in the drawing. 25

What I claim is—
